US0D1077123S

(12) **United States Design Patent** (10) **Patent No.:** **US D1,077,123 S**
(45) **Date of Patent:** **** May 27, 2025**

(54) **FIREARM SIGHT**

(71) Applicant: **HS Produkt D. O. O.**, Karlovac (HR)

(72) Inventors: **Mario Špine**, Karlovac (HR); **Dennis J. Reese**, Geneseo, IL (US); **Stephen H. McKelvain**, Geneseo, IL (US)

(73) Assignee: **HS Produkt D.O.O.**, Karlovac (HR)

(**) Term: **15 Years**

(21) Appl. No.: **29/911,113**

(22) Filed: **Aug. 29, 2023**

Related U.S. Application Data

(63) Continuation of application No. 29/735,750, filed on May 22, 2020, which is a continuation-in-part of application No. 35/506,775, filed on Feb. 13, 2019 (U.S. filing date under 35 U.S.C. 384), and having an international filing date of Feb. 13, 2019, now Pat. No. Des. 894,310.

(51) **LOC (15) Cl.** **22-01**

(52) **U.S. Cl.**

USPC **D22/109**

(57) **CLAIM**

The ornamental design for a firearm sight as shown and described.

DESCRIPTION

FIG. 1 is a back-right perspective view of the firearm sight showing our new design;

FIG. 2 is a front-left perspective view thereof;

FIG. 3 is a front-right perspective view thereof;

FIG. 4 is a top view thereof;

FIG. 5 is a front view thereof;

FIG. 6 is a left side view thereof; and,

FIG. 7 is a back view thereof.

The evenly broken lines disclose unclaimed portions of the firearm sight; the dash-dot broken lines depict unclaimed boundaries of the claimed design; the broken lines form no part of the claimed design.

1 Claim, 4 Drawing Sheets
